(Cl. D34—5)

This application is a division of application Ser. No. D. 84,053, filed by us on Dec. 7, 1964, entitled "Roller Coaster," now abandoned.

FIG. 1 is a plan view of a multiple-car unit for an amusement monorail or the like showing our new design;

FIG. 2 is a front elevational view of the multiple-car unit for an amusement monorail or the like shown in FIG. 1, showing our new design; and FIG. 3 is a side elevational view of the passenger car for a monorail or the like shown in FIGS. 1 and 2, showing our new design.

The broken lines indicating a monorail in the drawing are for illustrative purposes only.

We claim:

The ornamental design for multiple-car unit for an amusement monorail or the like, as shown and described.
